[57] CLAIM

The ornamental design for a pogo stick, substantially as shown and described.

DESCRIPTION

FIG. 1 is a front elevational view of a pogo stick showing our new design;

FIG. 2 is a right side elevational view thereof the side opposite being substantially a mirror image;

FIG. 3 is a top plan view thereof;

FIG. 4 is a top plan view thereof taken along line 4—4 in FIG. 3 shown partially in fragment;

FIG. 5 is a front elevational view thereof showing portions of the design in an alternate condition.

FIG. 1.

FIG. 2.

FIG. 3.

FIG. 4.
